CONTACT MEMBER FOR ELECTRONIC
TUBESWard W. Watrous, Jr., Chatham, N. J., assignor
to Westinghouse Electric Corporation, East
Pittsburgh, Pa., a corporation of Pennsylvania

Application February 19, 1949, Serial No. 77,328

5 Claims. (Cl. 250—27.5)

1 This invention relates to electronic tubes and other electrical devices, and especially to the metal cap often used with such devices, as an exterior contact element on the device envelope provided in addition to the usual lead-in contacts through the base. While the invention has been arbitrarily shown at an end of the device envelope directly opposite from the base, its location may be at any other part of the envelope where desired to position the same for lead-in or other purpose.

While the conventional method of forming such a connection has usually been to solder the lead wire to the inside of the cap, I have shown in my prior Patent 2,325,817 of August 3, 1943, a cap wherein the lead wire could be extended through the cap and soldered from the outside. That structure had pronounced advantages over the prior art, and the present invention proposes additional improvement thereover.

One object of the present invention is to overcome necessity for use of a reentrant type of cap.

Another object of the invention is to lessen the danger of cracking the glass or other envelope material around the lead-in wire either during fabrication or during use of the device.

A further object of the invention is to provide a structure wherein the lead-in wire may be welded to the cap in full view of the operator making the weld.

An important object of the invention is to provide a cap of the character indicated which avoids projections from the outer cap surface.

A still further object of the invention is to increase the tolerance in location of the cap in cementing or otherwise attaching the cap to the envelope.

Yet another object of the invention is to simplify the glass or container construction for the lead-in seal and for the mounting of the cap thereover.

Other objects of the invention will appear to those versed in the art to which it appertains, both by direct reference thereto and by implication from the context, as the description proceeds.

Referring to the accompanying drawing, in which like numerals of reference indicate similar parts throughout the several views:

Fig. 1 is a side elevation of an electronic tube having the present invention incorporated therewith;

Fig. 2 is a perspective view of the cap of the present invention;

Fig. 3 is a sectional view of a portion of the

electronic tube with the present invention applied in partially completed fabrication of the assembly; and

2 Fig. 4 is a view of a corresponding portion of the tube in elevation and with the present invention applied in its completed assembly and with the cap partially in section.

In the specific embodiment of the novel concept illustrated in said drawing, an electronic device, specifically a thyratron, has been arbitrarily selected with which to apply the present invention, but is to be understood at the outset that other specific constructions and types of electronic devices may equally well incorporate the innovation. The chosen device shown comprises a glass or other suitable vacuum-tight envelope 10 provided with a reentrant stem 11 at one end, which for orienting purposes will be referred to herein as the bottom or lower end of the device, and through said stem are sealed lead-in wires 12 for making connection to exterior terminal prongs 13 projecting from the bottom of a base 14 carried by the lower end of the envelope. Within the envelope the lead-in wires make appropriate connection to certain electrodes, such as to a cathode 15 and grid 16. Within and near the top of the envelope is another electrode, specifically an anode 17, and it is for purposes of providing an improved lead-in connection for this electrode that constitutes the basis of the present invention.

As shown, the glass of the envelope 10 is sealed around a suitable rigid lead-in post 18 which extends at one end into the envelope adequately for rigid attachment of the anode thereto, and extends at its other end to the exterior of the envelope and there is provided with a flexible lead-in connection or wire 19 constituting an integral extension of said post. This flexible lead-in connection may conveniently comprise stranded copper wire for maximum flexibility and minimum resiliency, and is shown bent into a close loop 19a giving to the connection appearance suggestive of a pigtail by which name said connection may be identified herein. This construction enables the anode to be rigidly and accurately mounted but provides a flexible pigtail the outer end of which can be attached to a metallic terminal cap 20 without need of careful alignment or fear of cracking the seal.

The terminal cap 20 comprises essentially a cylindrical neck portion 21 merging at its lower end into a flaring shoulder 22 which is bounded peripherally by a depending cylindrical flange 23. The terminal cap is applied to the end of

the envelope with the lead-in wire and pigtails projecting into the cylindrical neck portion thereof and with the cap substantially coaxial with the lead-in post 18. Suitable cement 24 is included between the cap shoulder and the envelope retains said cap in its assembled position.

The extreme end of neck portion 21 of the terminal cap away from the shoulder is provided with a transverse end wall 25 from which a tab 26 is struck thereby providing an aperture 27 of the same shape as the tab and with the tab integral, at one side of the aperture, with the main body of the end wall. Preferably in striking up said tab, it is bent outwardly substantially perpendicular to the end wall. The size of the aperture is made large enough to freely pass the end of the pigtails therethrough.

In fabrication and assembly, the envelope 10 is completed and provides the above-described rigid anode post 18 and pigtails flexible extensions 19 thereof projecting at the top of the envelope. The cap 26 is then applied on and cemented to the end of the envelope, care being taken in applying the cap to feed the projecting end of the pigtails through said aperture 27 so it will project in the vicinity of the upstanding tab 26. The said projecting end of the pigtails which, with the tab, is readily accessible to an operator and welding machine, is then spot welded to the face of the tab after which the tab is bent down to again lie in the plane of the end wall 25 of the cap entirely enclosing the lead-in wire or pigtails. The completed structure accordingly avoids any projection of tab or lead-in wire and presents to exterior view only a symmetrical cap with cylindrical neck and plane closed end, as shown in Figs. 1 and 4. It may be added, that by applying the cap as shown in the drawing so the tab is at the opposite side of the pigtails from the loop, the operation of closing the tab into the aperture flexes the pigtails at the loop without applying any descriptive strain upon the rigid post or glass seal.

I claim:

1. A contact member for a lead-in connection to an electric device, comprising a cylindrical portion and a transverse wall across an extreme end of said cylindrical portion, said transverse wall having a substantially planar surface and having an aperture, and a tab corresponding in size and shape to said aperture and said tab having two faces opposed on opposite sides of said tab, said tab being bendable at an edge of said faces into said aperture for locating one of said faces substantially in the plane of the outer surface of said transverse wall and for directing the other of said faces inwardly of the said cylindrical portion.

2. A contact member for a lead-in connection to an electric device, comprising a cylindrical portion and a transverse wall across an extreme end of said cylindrical portion, said transverse wall having a substantially planar surface and having an aperture, and a tab corresponding in size and shape to said aperture and said tab having two faces opposed on opposite sides of said tab, said tab being bendable at an edge of said faces into said aperture for locating one of said faces substantially in the plane of the outer surface of said transverse wall and for directing the other

of said faces inwardly of the said cylindrical portion and a lead-in wire attached to the inwardly directed face of said tab.

3. A contact member for a lead-in connection to an electric device, comprising a cylindrical portion and a transverse wall across an extreme end of said cylindrical portion, said transverse wall having a substantially planar surface and having an aperture, and a tab corresponding in size and shape to said aperture and said tab having two faces opposed on opposite sides of said tab, said tab being bendable at an edge of said faces into said aperture for locating one of said faces substantially in the plane of the outer surface of said transverse wall and for directing the other of said faces inwardly of the said cylindrical portion and a flexible lead-in wire attached to the inwardly directed face of said tab, said flexible wire extending transverse to said bendable edge of the tab and ending next a part of said face remote from the said bendable edge of the tab.

4. A contact member for a lead-in connection to an electric device, comprising a cylindrical portion and a transverse wall across an extreme end of said cylindrical portion, said transverse wall having a substantially planar surface and having a tab with two faces opposed on opposite sides of said tab, said tab being bendable at an edge of said faces for locating one of said faces substantially in the plane of the outer surface of said transverse wall and for directing the other of said faces inwardly of the said cylindrical portion and a flexible lead-in wire attached to the inwardly directed face of said tab, said flexible wire extending transverse to said bendable edge of the tab and ending next a part of said face remote from said bendable edge of the tab and the said flexible wire having a portion extending past the said bendable edge of the tab away from the tab and therebeyond having a pig-tail curl looping first toward the said attached end of the lead-in wire and away from said bendable edge of the tab and then toward the bendable edge and finally back to its original direction of projection from the tab whereby the pig-tail curl permits bending the tab and yet bending the tab to its position substantially in the plane of the transverse wall tends to tighten the pig-tail curl of said flexible lead-in wire.

5. A contact assembly comprising a glass envelope, a rigid post sealed through a wall of said envelope providing an outwardly projecting post end, a flexible pigtails extension on said outwardly projecting post end, a cap enclosing said pigtails extension, and a tab integral with said cap and welded to said pigtails extension.
